UNITED STATES PATENT OFFICE

ADDISON R. KLINGENSMITH, OF PARNASSUS, PENNSYLVANIA

COMBINATION LOCK SWITCH

Application filed December 6, 1927. Serial No. 238,069.

This invention relates to a means for controlling the ignition spark delivered by a battery to the combustion chambers of an internal combustion engine, used largely as motive power in automobiles or for other purposes. It comprises a series of outwardly extending movable operating levers, which when properly set will form one or more complete circuits to a series of combustion chambers, and 10 to independent points governing other circuits such as lighting systems, motor control systems, etc., as will be hereinafter described.

The principal object of the present invention is to prevent automobile thieves, or 15 other unauthorized parties from operating a "parked" or otherwise abandoned car, and to render it impossible, within a short time, to complete a necessary circuit to start the engine of the car. The invention comprises an 20 arrangement of parts and levers to be operated by those knowing a certain combination of said movement of levers.

The invention further consists in the details of construction and combination of parts, 25 as will be fully described hereinafter.

In the accompanying drawings:

Figure 1 is a sectional plan view of my improved device for making and breaking the electric circuit from the battery to the combustion chamber of an internal combustion engine and lighting systems used in an automobile or other driving means. The section being taken approximately on the line X—Y of Figure 2 of the drawings.

Figure 2 is a front view of the same.

Figure 3 is a rear elevation of the contact plate and movable contacts.

Figure 4 is a face view of said contact plate removed from the apparatus.

Figure 5, is a perspective view of one of the operating levers, detached from the apparatus.

Figures 6, 7 and 8 are detached detail views of the parts, rigidly connected to the 45 above mentioned operating lever.

Figure 9 is an enlarged central sectional view of a modified form of one of the said operating levers and its various component parts assembled.

Figure 10 is a front face view of the same.

Figure 11, is a detail sectional view of the lever socket of the operating lever showing a modified form in which the body is constructed in two parts joined together, said construction adapted to facilitate or make 55 easy the formation of the hollow spherical groove.

Figure 12 is a front view of the same.

Figure 13 is a face view of a portion of the contact plate showing a modified form of the 60 same.

Figure 14 is a face view of a modified form of one of the several movable contacts, detached from the operating lever, and

Figure 15, is an edge view of the same.

To construct a device in accordance with my invention and thereby afford a means that will effectually prevent the starting of the motive power, without knowing the combination, a box and cover are provided, adapted to be fastened in front of the driver, preferably directly in front and within easy reach of the same. This box 1, is to receive and contain a series of operating levers, each of which is analogous, the one with the other 70 and covered with a lid 2 hinged as at 3, as will be seen in Figures 1 and 2.

Arranged within the box 1 in parallel position are two partitions or supports 5 and 6 (see Figures 1, 2, 9, and 10) and a series 80 of cylindrical form plugs, each being provided with an exposed lever 10.

Each of the plugs, the one being identical with the other, is formed of hard rubber and is composed of several parts, they being supported and operated in the several openings 85 7. The exposed end 11, of the plug is provided with an integral handle 10, (as shown in Figures 1, 2, 5 and 9) or said handle may be loosely connected in sockets 12, (see Figures 9 and 10) the lever portion having at one end a ball 13, with outwardly projecting lug 13', operating in a groove 14.

This groove 14, and lug 13', will engage with each other and permit the plug to be 95 revolved about its center, and also permit the lever 10, to assume a vertical position by gravitation.

The barrel of each plug consists of three pieces carrying interposed parts, one 15, of 100

which keeps the plug in position. Another 16, positions the contact finger 17, in place and also supports the inner end of the plug and the several parts held rigidly together by suitable screws or rivets 18.

5 These contact fingers 17 consist of strips of metal and may be formed in various shapes, (as shown at Figure 1, 3, 6, 9 and 14) as circumstances require.

10 Arranged in circular form about each plug and carried by supporting plates 5 and 6 are a multiplicity of stationary contact plugs 19, a select number of which are connected to the active circuits, the large majority being 15 inactive and put in place to deceive and render the chances of unauthorized persons attempting to complete one or more circuits, highly improbable and almost impossible in a short period of time, without knowing the 20 combination.

25 The several electrical conductors A and B (see Figure 1) are attached to the battery (not shown) and to the selected contact points 19. The circuits in this case lead to the several combustion chambers and to the lighting apparatus, or to any other desired point where motive power or other service is required.

30 In operation:—By the aid of a knob 4, (Figure 1) the door of the cover is opened, exposing the series of levers 10, to view. It will be difficult for the operator to single out the proper levers to move in order to complete the circuit to any desired point, such as 35 the combustion chambers or to the lighting circuit, as the number of contact points may be increased to and including several thousand. As the lever is moved an audible sound is made, as each point 20, passes over 40 either the contact 19, or any of the slight depressions 21, which are not in the circuit.

45 At Figure 3 of the drawings, I have shown two plates, each formed with those above mentioned depressions and contact points. The one plate 21', is in circuit with the lighting apparatus and the other 21'' is for the motive power.

50 It will be seen that any person, not knowing the exact combination of numbers or letters, if such are indicated, or the exact position of the levers 10, as presented from the front of the box 1, will not be able to complete the circuit.

55 This will deprive any thief from operating a car equipped with this improvement unless he has several hours to work out the combination.

60 It is obvious that the details of construction may be changed without departing from the spirit of the invention.

65 What I claim as new is:—

1. In combination with a lock of the character described, a rotatable plug provided with a spherical recess having an annular groove with a pocket, a loose lever having a

spherical head with a radial projection operating within said recess, and a means for loosely holding the two parts together.

2. In combination with a lock of the character described, a rotatable cylindrical plug, 70 provided with a spherical recess having an annular groove and pocket, a loose lever having a spherical head provided with a radial projection to engage with said pocket and a contact arm fixed to the inner end of the said plug.

75 3. In combination with a lock of the character described, a rotatable plug provided at one end with a spherical recess having an annular groove with a pocket, a finger lever formed with a spherical head and integral, radial projection operating within said spherical recess and pocket, a means for holding the parts together and contact fingers fixed to the inner end of said plug, in such manner, that the lever when at rest will 80 assume a vertical position by gravitation.
